UNITED STATES PATENT OFFICE.

CHARLES T. GAITHER, OF YOUNGSTOWN, OHIO.

CARBURETER.

No. 857,275.

Specification of Letters Patent.

Patented June 18, 1907.

Application filed February 1, 1906. Serial No. 298,962.

To all whom it may concern:

Be it known that I, CHARLES T. GAITHER, a citizen of the United States, and a resident of the city of Youngstown, county of Mahoning, and State of Ohio, have invented certain new and useful Improvements in Carbureters, of which the following is a description.

My object is to produce a self-contained carbureter which may be more or less automatic in its action, and which will overcome the difficulties heretofore experienced in devices of this class in regard to the control of the admission of air after the speed of the engine has reached a certain limit. When the engine to which the carbureter is attached has reached a certain speed, it is desirable to increase the air entering into the gas mixture without a corresponding increase of the gas forming liquid; and my object is to provide a valve which will be self-operated and which will allow the air entering the gas chamber to be increased without increasing the suction of the gasolene, or other fluid, at the same ratio as if the air was freely admitted to pass the needle valve and thus increase the supply of liquid.

My invention also relates to an improved floater for operating the check valve governing the supply of gasolene, and to the method of operating the hinged valve which governs the supply to the engine.

The details of a construction in which I have embodied my invention will be herein-after more fully set forth.

35 In the drawings forming part of this application, Figure 1 is an elevation of a carbureter having my improvements embodied therein. Fig. 2, is a plan view of the same. Figs. 3 & 4 are sections taken on the lines 3—3 and 4—4 respectively, of Fig. 2, looking in the direction of the arrows. Fig. 5 is an elevation of a part of the carbureter showing the improvements for operating the hinged valve. Fig. 6 is a perspective view 40 of my improved floater. Fig. 7 is a plan view of a portion of the same showing its adjustment to the valve, and Fig. 8 is a view of the valve which governs the admission of air into the gas chamber.

50 In the formation of my carbureter, I provide a receptacle 1 for retaining the suitable supply of gasolene, or other liquid, which is adapted to operate a motor such as is commonly used on automobiles. This chamber 55 is preferably cylindrical, and from this illustration it will be seen that it is provided with

an outer case 2 having an interior cylindrical tube 3 extending from the bottom 4 to substantially the top of the outer casing, whereby an annular chamber 5 is formed about the 60 cylindrical body 3 which is adapted to serve as a reservoir for the reception of the gasolene such as is used in the machine. I will use the word "gasolene" in the description of this invention, although it is understood that 65 liquids of similar character may also be used in the present device. The interior of this cylindrical body 3 is the chamber in which the air is adapted to unite with the liquid as it sprays from the needle valve, thus 70 forming a proper mixture which passes upwardly and into the motor for use.

The cross piece 6 is provided at the bottom of the carbureter, which crosses the center of the opening at the end of the cylinder 3 and is 75 provided with a depending stem 7 having a central bore 8 in which is provided a needle valve 9. The nozzle 10 of this valve projects upwardly into the cylinder 3 and has suitable openings on the end for spraying the liquid 80 into the chamber. The valve is adapted to be operated by the spindle 11 which projects downwardly beyond the neck 7 and which is screw-threaded in the latter at the point 12. The handle 13 is provided on the end of the 85 spindle, and a suitable packed connection 14 holds the spindle properly in connection with the neck 7.

By turning the handle 13 the valve is caused to raise and lower, so that the conical 90 end 15 rises and falls at a point near the shoulders 16 of the nozzle, for the purpose of increasing or decreasing the flow of liquid which enters the nozzle through the passage 17, which latter opens into the chamber or 95 reservoir 5.

The chamber 5 is supplied with gasolene by means of a suitable pipe running from the source of supply and connected to the plug 18 at the lower end of the chamber 5. The 100 supply received through this plug is adapted to be governed by a check-valve which is constructed as follows: A vertical chamber 19 (see Fig. 4) which is offset from the side of the reservoir, is provided with a block 20 105 which is raised and lowered therein by means of a screw 21 which latter is accessible from the top of the chamber. To this block is pivoted at the point 22 an arm 23 which is also pivoted at the point 24 to the plunger 25. The arm 23 is adapted to carry a floater 110 26 which is cylindrical and which lies loosely

in the space in the chamber 5. When the liquid in the chamber 5 starts to rise by entering through the plug 18, at a certain point it causes the floater 26 to rise, then the plunger 25 by reason of the fixed pivot 22 will be caused to rise with the arm 23 when the end 27 of the plunger will be seated on the ends 28 of the plug 18, thus cutting off further admission of the liquid.

10 Through the adjustment of the plug 20 the pivoting point of the lever 23 may be raised or lowered in order to allow for a greater or less amount of liquid entering into the chamber 25 in order to raise the floater. This 15 floater forms one of the improved features of my invention, and is constructed as follows: Heretofore great difficulty has been experienced where cork has been used in such devices, by reason of the same being chipped 20 or having small particles become separate, thus clogging the working of the device, and where metal cylinders have been used for floaters they have also proven unsatisfactory. I therefore provide a floater which consists 25 of the ring of cork which is dipped in an electrotype bath so that the cork is plated with the electroplate solution which substantially adheres and properly coats the cork for the purpose of preventing any crumbling or falling away of the cork when in use. This has 30 proven very satisfactory, and I deem it an important step in this art.

For the purpose of governing the entry of the air into the mixture, I have provided a 35 very novel valve which, when the speed of the engine reaches a certain speed, any increase of speed above this point will cause the air to enter the chamber in such a way as not to increase the spray of the needle valve 40 in the same proportion that it would if the suction of air were allowed to fully operate upon the needle valve. The device which I have provided for this purpose is self-operated. That is, when the speed of the engine increases above the point referred to this valve 45 will of itself operate for the purposes stated. Broadly considered, this valve consists of a resilient coil which governs the entry of air into the mixing chamber, and, when the suction caused by the increase of speed in the engine increases it, will cause the coil to elongate so that the air will pass between the parts of the same and enter the mixing chamber without passing directly past the needle 50 valve when entering the chamber. This is for the purpose of preventing too much suction on the end of the needle valve when the speed of the engine passes beyond the period set forth, which, for the purpose of convenience, I will call the abnormal speed. The 55 form of valve which I have used for this purpose, and which I prefer, is shown in Fig. 8 and consists of a spiral wound wire spring 29 which is wound spirally and conically so as to 60 form a conical shape having a cylindrical end

30 at the top. The various turns of this coil during their resting position are adapted to remain in contact with each other, so that little or no air will enter between them.

When the valve is in use, as is shown in Fig. 3, the normal supply of air coming into the mixing chamber enters underneath this resilient valve, passes up through the cylindrical end 30 and then passes the end of the nozzle of the needle valve, causing the liquid 75 which comes out of the latter to be sprayed and pass upwardly in the nature of a gas mixture into the engine. When the engine reaches the abnormal speed I have described, the suction in this chamber will become so 80 great that the resilient valve will be drawn upwardly thereby, and by reason of the lower coils being rigidly held by the interior cylinder 31 which secures the same against the shoulder 32, the various turns of the coil 85 will separate causing a space between them which will admit the excess of air at such a point as to have little, if any, effect on the nozzle. As the cylindrical end 30 of the valve is constructed there will be very little, and 90 possibly no, separation of the coils when the valve starts to rise, so that the increased suction affecting the nozzle will only be such as enters through the cylindrical part. If desired, this cylindrical end might be made of a 95 solid piece. Or it might be eliminated altogether, in which event I believe that the valve would not operate quite as efficiently. When the speed of the engine is decreased to the normal speed, or below it, the coils immediately close upon each other and the admission of air continues under the valve and 100 through the cylinder 30.

For the purpose of inclosing the various parts I provide a head 33 which is secured to the cylinder 2 by suitable bolts 34, which clamp the head thereon by means of projecting lugs 35 & 36 on the head and cylinder, respectively. Extending upwardly from the head is a cylinder 37 which forms a 105 continuation of the cylinder 3, and to which the pipe running to the engine is attached. When the parts are assembled, as shown in Fig. 3, the cylinder 3 is adapted to lie in a recess 38 in the head, so that the mixing chamber will continue from the cylinder 3 into the cylinder 37. 110

For the cylinder 37 I provide a hinged valve with a novel means for operating the same. The operating lever is adapted to have attached to it any form of operating lever. The lower end of the lever is pivoted at the point 40 to a hinge pin 41 which passes through and is journaled in the sides of the cylinder 38. This hinge carries the valve 42 115 which is adapted to close, or partly close, the interior of the cylinder 37. In other words, it is to govern the supply of the mixture as it passes on to the engine.

The lever 39 has two radially projecting 120

arms 43 & 44 which project downwardly and outwardly from the point of pivot and are controlled and are engaged by a stop 45 which may be formed integral with the head 33 and projects upwardly therefrom. The arm 44 is provided with an adjusting screw 46, and also a screw 47 adapted to act as a set screw for the first mentioned screw 46 when the latter has been adjusted to its proper position. The spring 48 is secured to a portion of the head by means of a screw 49 so as to project upwardly and lie in the path of the screw 46, a distance away from the stop 45. When this lever 39 is operated for the running of the engine, the same is brought to the position shown in Figs. 1 & 3, when the screw 46 contacts with the spring 48 and the valve 42 is then almost closed, so that just sufficient of the gas mixture passes upwardly to merely keep the engine going. When it is desired to entirely shut off the supply of the mixture it will be necessary to further move the lever 39 against the resistance of the spring 48 until it contacts with the stop 45, when the valve 42 will entirely close the cylinder 37. The movement of the lever 39 in a reverse direction will be governed by the arm 43 which will contact in the extreme movement of the stop 45. It is obvious that the purpose of this arrangement is to have the lever almost close the valve when it will contact with the spring, and to entirely cut off the supply it would be necessary to further operate the lever against the action of the spring.

A drain cock 49 is provided at the bottom of the reservoir for the purpose of draining the latter.

Modifications may be made in the resilient air governing valve, and to a certain extent in its location, without departing from the broad spirit of my invention, as I believe myself to be the first to produce a valve of this character for this purpose, and without departing from the spirit of my invention as recited in the annexed claims.

Having described my invention, what I claim is:

1. A carbureter comprising a mixing chamber having a means for admitting liquid therein, and a valve effecting the entry of air into said chamber, said valve comprising resilient separating parts through which air is adapted to pass when the said parts separate, and means for securing one portion of the coil, and a free end on the coil adapted to be raised and the coils separated by the suction of the carbureter.

2. A carbureter comprising a mixing chamber having a sprayer therein, an air inlet for said chamber, and means for governing the entry of air therein comprising a valve composed of a resilient coil, the parts of which are adapted to separate and allow air to pass between, the lower portion of the valve being

secured and the upper portion free, whereby the suction of the carbureter will cause the valve coils to open.

3. A carbureter comprising a mixing chamber having a liquid inlet, and an air inlet to said mixing chamber, and a valve effecting the inlet of air into said chamber, comprising a spiral of resilient material in which the spirals are adapted to separate, to allow air to pass therebetween, the lower end of the valve being secured and the upper end free, so that the suction of the carbureter will separate the coils and whereby they will be returned by the resiliency of the coils.

4. A carbureter having a mixing chamber, with a liquid inlet therein, and having an inlet for air, and a valve effecting the inlet of air, said valve comprising a conically shaped member with the larger portion at the bottom, formed of spirally wound resilient material, the coils of which are adapted to separate, thereby providing spaces for the admission of air, the valve being secured near the bottom and the top being free to move upwardly.

5. A carbureter, comprising a mixing chamber, a nozzle for admitting liquid into said chamber, an air inlet for said chamber, a cylinder surrounding the nozzle and a valve composed of resilient coils adapted to be separated by the suction in the carbureter to permit air to enter said mixing chamber, in addition to the air admitted through the said cylinder.

6. A carbureter comprising a mixing chamber, having a nozzle for the admission of liquid, a member surrounding the nozzle and through which air is admitted into said chamber near the nozzle whereby the suction of the engine will cause the liquid to spray from said nozzle, and a valve for governing the further entry of air into the mixing chamber, said valve being adapted to be operated by the suction of the engine.

7. A carbureter comprising a mixing chamber, having a nozzle for the admission of liquid, a member surrounding the nozzle and through which air is admitted near the nozzle and a valve adapted to control the further entry of air into the mixing chamber, comprising resilient coils, one end of said valve being secured, whereby the suction of the engine will cause the coils to separate and admit air therebetween.

8. A carbureter having a mixing chamber, a nozzle for admitting liquid therein, an air inlet to said chamber and a valve having a cylindrical top forming an inlet for the admission of air directly to the nozzle, and a curved lower portion composed of resilient coils secured at the lower portion, and free at the top, to be separated by the suction of the engine to form an additional air inlet to the said mixing chamber.

9. A carbureter having a mixing chamber,

1. A nozzle for the admission of liquid therein, a valve having a cylindrical top 30 surrounding the nozzle, and forming an air passage between the nozzle and top 30, whereby air is admitted directly to the nozzle top, the said valve extending downwardly therefrom in a conical form and projecting outwardly, said conical portion being formed of coils of resilient material, the lower portion of which is secured, and the upper portion free whereby the suction of the engine will cause the coils to separate and admit air to enter the mixing chamber independent of the air passage in the cylindrical part 30.
2. A carbureter having a mixing chamber, a nozzle for the admission of liquid therein, a valve having a cylindrical top 30 surrounding the nozzle, and forming an air passage between the nozzle and part 30, whereby air will be admitted at the nozzle, the said valve extending outwardly therefrom, and comprising resilient coils, which are adapted to lie in contact with each other and adapted to be separated by the suction of the engine, to allow for the further admission of air, means securing the lower portion of the valve, said cylindrical portion 30 being free and adapted to rise when the coils are separated.

3. A carbureter having a cylinder forming a mixing chamber and having a shoulder, a nozzle for the admission of liquid into the mixing chamber and a valve for effecting the admission of air into the mixing chamber, comprising a plurality of resilient coils adapted to be separated for the admission of air therebetween, and a cylinder adapted to secure a portion of the valve on the shoulder of the said first mentioned cylinder.

4. A carbureter having a mixing chamber, a valve adapted to admit liquid into said chamber, and a valve adapted to admit air into said mixing chamber below the nozzle of the liquid valve, and means for preventing the air so admitted from directly affecting the said nozzle, the said air valve comprising resilient coils which are secured near the bottom, and having the top free and adapted to be separated by the suction of the engine.

Signed at the city of New York, county of 5 New York, State of New York, this 23rd day of January, 1906.

CHARLES T. GAITHER.
